UNITED STATES PATENT OFFICE.

WILLIAM F. CHRISTIANSEN, OF CHICAGO, ILLINOIS, ASSIGNOR TO SHARP & SMITH, OF CHICAGO, ILLINOIS, A CORPORATION OF ILLINOIS.

BRANDING-IRON.

1,101,616.

Specification of Letters Patent. Patented June 30, 1914.

Application filed December 5, 1913. Serial No. 804,799.

To all whom it may concern:

Be it known that I, WILLIAM F. CHRISTIANSEN, a citizen of the United States, residing at Chicago, in the county of Cook 5 and State of Illinois, have invented a new and useful Improvement in Branding-Irons, of which the following is a specification.

My invention relates to certain new and useful improvements in branding-irons and 10 is fully described and explained in the specification and shown in the accompanying drawings, in which:

Figure 1 is an elevation of my improved device; Fig. 2 is a section through the lower 15 portion of the same; Fig. 3 is an end view of the lower end of the device; Fig. 4 is a section through the upper part of the device, and Fig. 5 is a section through the liquid nozzle and adjacent parts on an enlarged scale.

Referring to the drawings, 6 is a reservoir for a supply of ether, which is the preferred fuel for use in connection with my branding-iron. The reservoir is surrounded 25 by a non-metallic sleeve 7, so as to afford a relatively-cool surface to be grasped by the user. The sleeve is held in place by a ring 8 screwed on the upper end of the reservoir. The reservoir is closed at its upper end by 30 a plug 9 in which is a threaded nipple 10 which receives a needle-valve rod 11, a packing 12 held in place by a packing nut 13 being provided in accordance with common practice.

In the lower part of the reservoir is a 35 nipple 14, in the upper part of which is a plug 15 continued upward to form a tube 16 which receives and guides the valve-rod 11 and is provided at its lower end with a 40 seat 17. The space within the nipple 14 below the plug 15 is filled with material affording reticulations for the passage of vapor. This material may be either crumpled metal gauze, or fibrous vegetable material, 45 its purpose being to arrest any liquid which might issue from the needle-valve and hold it in suspension until vaporization can occur. The lower end of the nipple 14 receives a nozzle 18 at the end of which is set 50 a small block 19 of stone or glassy material having a central nozzle hole.

The structure thus far described is obviously such that ether vaporized by heat conducted to the reservoir will issue from the

needle-valve under the control thereof, and 55 thence pass out of the nozzle. To the lower end of the reservoir is screwed a mixing tube 20 having a series of perforations 21 at its upper end adjacent to the nozzle from which the vapor issues. Air, of course, enters through the perforations 21 and is mixed with the vapor within the mixing tube. The lower end of the mixing tube is closed by a cap 22 having perforations 23 through which the mixed air and vapor pass 60 into an enlarged head 24 having at its upper end a nut 25 screwed on the mixing tube. The neck has perforations 26 for the admission of additional air and the head has lower down a series of perforations 27 for 65 the escape of products of combustion. The head is provided at its lower end with flanges 28 into which can be slipped interchangeable branding plates 29 provided with raised letters or characters, the plates being adapted 70 to be held in position by a button 30.

The operation of the present device will be readily apparent. The fuel in the reservoir passing from the nozzle as heretofore set forth picks up air within the mixing tube 80 and issues from the cap thereof into the head in the form of a combustible mixture which burns within the head, thus heating the branding-plate in place to the requisite temperature to do its work.

The device is simple and convenient and will hold its heat for a long time. It is thus far preferable to the usual device which must be heated up before being used, since 85 the present device, carrying its own heating means, can be used repeatedly without intermediate heatings. Furthermore, the interchangeable character of the branding-plates fits a single device for a large amount of use.

I realize that considerable variation is possible in the details of the construction herein shown, and I do not intend to limit myself thereto, except as pointed out in the following claim, in which it is my intention 90 to claim all the novelty inherent in the device as broadly as the state of the art will permit.

I claim as new and desire to secure by Letters Patent;—

In a branding-iron, in combination, a liquid fuel reservoir, a non-metallic casing surrounding and spaced apart from said reser-

voir, a plug at one end of said reservoir, a needle valve coacting therewith and operable from the other end, liquid arresting means adjacent said plug, a nozzle, a relatively long mixing chamber having air inlets adjacent said nozzle, a perforated cap at the end of said chamber, a hollow head inclosing said cap having separate air inlets and outlets for the escape of the products of com-

bustion, and a removable branding plate in 10 said head.

In testimony whereof I have hereunto set my hand this 2nd day of December, 1913.

WILLIAM F. CHRISTIANSEN.
